UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed October 5, 1925. Serial No. 60,378.

To all whom it may concern:

Be it known that I, EARL B. LEAR, a citizen of the United States, and a resident of Phillipsburg, county of Warren, and State of New Jersey, have invented a certain Double-Drum Hoist, of which the following is a specification, accompanied by drawings.

This invention relates to hoists, but more particularly to a power driven hoist of the double drum type.

One object of the invention is to enable two drums, as for instance, a haulage drum and a tail rope drum to be driven from a common source of power.

Another object is to arrange the source of power between the drums for actuating the hoist. A further object is to automatically connect one or the other of the drums with a common source of power in accordance with the direction of rotation of the power element.

Other objects will in part be obvious and in part pointed out hereinafter.

The invention consists of the combinations of elements, features of construction and arrangement of parts having the general mode of operation substantially as hereinafter described and more particularly pointed out in the appended claims and illustrated in the accompanying drawings, in which—

Figure 1 is a longitudinal view in elevation, partly in section, of a hoist of the double drum type showing one of the drums connected to be rotated by the driving shaft.

Figure 2 is a view similar to Figure 1 showing the other drum connected to be driven by the driving shaft, and

Figure 3 is a transverse view through Figure 1 looking in the direction of the arrows.

Referring to the drawings, the base plate A which supports the hoist is mounted on a bed plate B to enable the hoist to be rotated about a vertical axis for locating said hoist with respect to the work. Any suitable means may be employed for clamping the hoist to the bed plate, in this instance a bolt C is shown. In addition to serving as a means for clamping the hoist on the bed plate, the bolt C may also serve as a pivot about which the hoist may be rotated.

Disposed on opposite sides of the base plate A are end frames D and E. Gear casings F and G are preferably formed integrally with the frames D and E respectively

and are provided with suitable covers H and J for sealing one side of said casings. The covers H and J are held in place by suitable bolts K. In addition to sealing the gear casings, the covers H and J also provide a support for opposite ends of a driving shaft L. In this instance the driving shaft L is formed in two parts and is preferably provided at its ends with frictionless bearings O arranged in the gear casings H and J.

In accordance with the present invention, a motor, which is preferably of the type disclosed in the pending U. S. application of Fred M. Slater for a gear motor, Serial No. 56,681 filed Sept. 16, 1925, assigned to the Ingersoll-Rand Company, assignee of the present invention, is arranged on the shaft L intermediate the frames D and E. The motor illustrated is of the gear type having the gear P and pinion Q encased by a casing R and side covers S and T. In this instance the gear P is keyed to a bushing U having a rectangular bore V to receive correspondingly formed portions W of the shaft L. Frictionless bearings X are provided for the bushing U. Similarly, frictionless bearings Y are provided for the pinion Q and are journaled on a stationary shaft Z about which the pinion Q rotates.

Motive fluid for actuating the motor is admitted through a connection b (Figure 3) and is controlled by a suitable throttle valve (not shown) in a valve chest c having a throttle lever d. Ports e and f leading from the valve chest c supply motive fluid to the gear P and pinion Q. The ports e and f are so arranged with respect to each other than when motive fluid is admitted through one port or set of ports for driving the motor in one direction, the other port or set of ports will serve as exhaust ports.

Pillars g and h preferably formed integrally with the motor covers S and T are secured to the frames D and E respectively by means of screws k and provide a convenient bearing for a haulage drum o and a tail rope drum p located on opposite sides of the motor.

In order to connect the drums o and p to be driven by the driving shaft L, an internal gear q is preferably formed integrally with the flanges r of said drums to mesh with intermediate pinions s carried by counter-shafts t. The countershafts t are provided with frictionless bearings u and v in the

frames D and E and the covers H and J respectively. A clutch member w is mounted on each countershaft t and is secured thereto preferably by a key x. Intermediate spiralled gears y are arranged loosely on the countershafts t and mesh with spiral pinions z on the outer ends of the shaft L. The intermediate spiral gears y are arranged slidably on the countershafts t and carry 10 clutch teeth 2 adapted to cooperate with the clutch members w for connecting the drums with the driving shaft.

Usually in hoists of this type, a brake is provided to prevent rotation of the drums 15 when one or the other of said drums is disconnected from the driving shaft. In this instance, a separate brake is provided for each drum and brake bands 3 are accordingly arranged about the flanges r of the 20 drums o and p to encircle said flanges. The one end 4 of the bands 3 is in this instance secured to a pin 5 which also serves as a pivot for an eye-bolt 6 upon which the other end 7 of said bands is secured slidably. Springs 25 8 are disposed on the bolts 6 to constantly force the ends 7 of the bands 3 outwardly against the thumb nuts 9 and cause the bands 3 to grip the flanges r when the drums tend to rotate in one direction. Whenever 30 the drums rotate in the opposite direction, the drums acting against the brake bands 3 will tend to raise the free ends of the eye-bolts 6 and thus release the friction of the bands upon said flanges.

Means are provided for simultaneously sliding the intermediate gears y and to hold said gears in spaced relation with respect to each other. To this end an inwardly extending flange 10 is formed on each gear. A rod 12 is arranged slidably through a sleeve 13 secured at its ends to the frames D and E, preferably beneath the drums o and p. The rod 12 is provided at one end with a groove 14 to engage the flange 10 of one gear y. A 45 collar 15 is press fitted or otherwise secured on the other end of said rod and with a screw 16 forms a similar groove 14 to engage the flange on the other gear y.

In the operation of the device assuming 50 that the haulage drum is being rotated as indicated in Figure 1 and that it be desired to disconnect the haulage drum o from the driving shaft and to connect the tail rope drum p to be driven by the driving shaft 55 L, the throttle lever d may then be moved to position for admitting the pressure fluid through the port f to cause the shaft L to rotate in the direction of the arrow 17 in Figure 3. With the shaft L rotating in this 60 direction, the spiral pinions z will force the intermediate gears y in the direction of the cover J and force the clutch teeth 2 into engagement with the clutch member w on the tail rope drum side of the hoist. Simultaneously the clutch teeth 2 on the inter-

mediate gear y on the haulage drum side of the hoist will be moved out of engagement with its clutch member w.

The advantages of the invention consists in the fact that a hoist constructed in accordance with the foregoing description is well balanced and is rigid in construction. Another advantage is one drum or its driving mechanism may be disassembled without disturbing the other drum or its driving mechanism. A still further advantage is that the parts comprising the driving elements for the drums are symmetrical and are therefore interchangeable.

I claim:

1. In a hoist, the combination of a frame, a driving shaft supported by the frame, a pair of drums rotatable about said driving shaft, a fluid actuated motor between the drums, intermediate gears for connecting the drums to be rotated by the driving shaft, and means for automatically shifting said gears to connect one or the other of said drums with the driving shaft in accordance with the direction of rotation of said motor.

2. In a hoist, the combination of a frame, a driving shaft supported by the frame, a pair of drums rotatable about said driving shaft, a fluid actuated motor between the drums, intermediate gears for connecting the drums to be rotated by the driving shaft, and a rod for automatically shifting said gears to connect one or the other of said drums with the driving shaft in accordance with the direction of rotation of said motor.

3. In a hoist, the combination of a frame, a driving shaft supported by the frame, a pair of drums rotatable about said driving shaft, a fluid actuated motor between the drums, intermediate gears for connecting the drums to be rotated by the driving shaft, and a collared rod for automatically shifting said gears to connect one or the other of said drums with the driving shaft in accordance with the direction of rotation of said motor.

4. In a hoist, the combination of a frame, a driving shaft supported by the frame, a pair of drums rotatable about said driving shaft, a fluid actuated motor between the drums, an intermediate gear at each end of the hoist for connecting the drums to be rotated by the driving shaft, a flange on each gear, and a collared rod cooperating with the flanges for automatically connecting one of the drums with the driving shaft and simultaneously disconnecting the other said drum from the driving shaft in accordance with the direction of rotation of the motor.

5. In a hoist, the combination of a frame, a driving shaft supported by the frame, a pair of drums rotatable about said driving shaft, a fluid actuated motor between the drums, an intermediate gear at each end of the hoist for connecting the drums to be ro-

- 5 tated by the driving shaft, an inwardly extending flange on each gear, and a longitudinally slideable collared rod engaging the flanges whereby the gears may be shifted simultaneously to connect one of the drums to be rotated by the driving shaft and to disconnect the other drum from the driving shaft in accordance with the direction of rotation of the motor.

10 6. In a hoist, the combination of a frame, a driving shaft supported by the frame, a pair of drums rotatable about said driving shaft, a fluid actuated motor between said drums for rotating the drums, a casing for said motor, means on the casing to form bearings for the drums, intermediate gears for connecting the drums to be rotated by the driving shaft, and a rod for shifting the gears to connect one or the other of said drums with the driving shaft in accordance with the direction of rotation of the motor.

15 7. In a hoist, the combination of a frame, a driving shaft supported by the frame, a pair of drums rotatable about said driving shaft, a fluid actuated motor between said drums for rotating the drums, a casing for said motor comprising side covers, means on said side covers to form bearings for the drums, intermediate gears for connecting the drums to be rotated by the driving shaft, and a rod for shifting the gears to connect one or the other of said drums with the driving shaft in accordance with the direction of rotation of the motor.

20 8. In a hoist, the combination of a frame, a driving shaft supported by the frame, a pair of drums rotatable about said driving shaft, a fluid actuated motor between said drums for rotating the drums, a casing for said motor comprising side covers, hollow pillars on the side covers to form bearings for the drums, intermediate gears for connecting the drums to be rotated by the driving shaft, and a rod for shifting the gears

25 to connect one or the other of said drums with the driving shaft in accordance with the direction of rotation of the motor.

30 9. In a hoist, the combination of a frame, a driving shaft supported by the frame, two drums rotatable about the driving shaft, a fluid actuated gear motor between the drums, a gear casing at each end of the hoist, a counter-shaft in each casing, an intermediate gear on each shaft connected to transmit rotation of the driving shaft to a drum, clutch teeth on said gears, a clutch member keyed on each counter-shaft, and a slideable rod connecting the gears whereby the clutch teeth on one gear are moved out of engagement with one clutch member while the clutch teeth on the other gear are simultaneously moved into engagement with the other clutch member in accordance with the direction of rotation of the motor.

35 10. In a hoist, the combination of a frame, a driving shaft supported by the frame, a spiralled pinion at each end of the driving shaft, two drums rotatable about the driving shaft, a fluid actuated gear motor between the drums, a gear casing at each end of the hoist, a countershaft in each casing, an intermediate spiral gear on each shaft in constant mesh with the spiral pinion connected to transmit rotation of the driving shaft to a drum, clutch teeth on said gears, a clutch member keyed on each countershaft, and a slideable rod connecting the gears whereby the clutch teeth on one gear are moved out of engagement with one clutch member while the clutch teeth on the other gear are simultaneously moved into engagement with other clutch member in accordance with the direction of the rotation of the motor.

40 In testimony whereof I have signed this specification.

EARL B. LEAR.
